UNITED STATES PATENT OFFICE.

SALVATORE D. TOMASO, OF CHICAGO, ILLINOIS, ASSIGNOR OF ONE-HALF TO ROBERT E. HULSMAN, OF CHICAGO, ILLINOIS.

BURGLAR-ALARM SYSTEM.

1,157,601.

Specification of Letters Patent. Patented Oct. 19, 1915.

Application filed March 26, 1915. Serial No. 17,155.

To all whom it may concern:

Be it known that I, SALVATORE D. TOMASO, a citizen of the United States, residing at Chicago, in the county of Cook and State 5 of Illinois, have invented certain new and useful Improvements in Burglar-Alarm Systems, of which the following is a specification.

The present invention is designed to provide an improved burglar alarm system 10 characterized by a phonograph or other talking machine and a telephone system, whereby a message is automatically sent to a police station or other place when an intruder attempts to enter the house in which the system is installed.

The invention has for its object to provide a novel and improved arrangement of electric circuits and switches whereby the 20 operation of the system is controlled, and also to provide novel and improved actuating means for the talking machine.

Other objects and advantages of the invention will be pointed out in the detailed 25 description appearing hereinafter, and in order that the invention may be better understood, reference is had to the accompanying drawings, in which—

Figure 1 is an elevation of the apparatus; 30 Fig. 2 is a horizontal section on the line 2—2 of Fig. 1; Fig. 3 is an inverted horizontal section on the line 3—3 of Fig. 1 and the protective circuit shown diagrammatically; Fig. 4 is a cross-section on the line 35 4—4 of Fig. 2, and Fig. 5 is a cross-section on the line 5—5 of Fig. 3.

Referring specifically to the drawings, 5 denotes a door and 6 a window of the house in which the system is installed. In the 40 house is located a telephone, the transmitter of which is shown at 7, the same being mounted in a box 8 placed at any convenient location in the house. The box is provided with a suitable closure 9, and it contains 45 two shelves 10 and 11, respectively, the transmitter being mounted on the top shelf 10. On the bottom shelf 11 is mounted a talking machine having a record cylinder 12 and a sound box 13, to which latter is 50 connected a horn 14 arranged to conduct to the transmitter the sound waves from the record cylinder, so that when the telephone circuit is closed and the talking machine is started, an alarm is sent out over the line. 55 The record cylinder contains the message to

be sent, which will be a call for "central" to make connection with police and a call for police assistance, together with the location of the house; or the telephone may be connected directly with police headquarters. 60

The following means are provided for operating the talking machine: The sound box 13 is carried by an arm 15 extending from a carriage 16 slidably mounted on a shaft 65 17. From the carriage also extend two arms 18 and 19, respectively. The arm 18 has a nut 20 at its outer end which engages the threads of a feed screw 21 extending parallel to the shaft 17. The feed screw has a 70 mandrel 22 which carries the record cylinder 12. Thus, when the feed-screw is in motion, the stylus of the sound box travels lengthwise of the record cylinder and the latter also rotates. This construction and 75 operation of the talking machine is the same as that of an ordinary Edison phonograph.

In order that the message may be repeated, a second feed-screw 23 is provided which returns the carriage 16 and the sound box 13 80 to starting position. The feed-screw 23 is parallel to the feed-screw 21, and a driving connection between the same is provided, which may be intermeshing pinions 24 and 25 on the respective feed-screws. The arm 85 19 has pivoted to its outer end, as indicated at 26, a finger 27, the free end of which is shaped to engage the threads of the feed-screw 23. This finger is not in engagement with the threads of the feed-screw 23 when 90 the carriage 16 is being fed forward, but hangs down in front of said feed-screw, and at the end of the forward movement of the carriage the finger is automatically engaged with the threads of the feed-screw 23 to return the carriage. To effect this automatic engagement of the finger, there is mounted 95 on the feed-screw 23, to turn therewith, a disk 28 having a stud 29 projecting from its face. The disk is so located that when the carriage is at the end of its forward movement the stud strikes a shoulder 30 on one side of the finger, thus lifting the same, and also the arm 19, and when the stud clears the shoulder, the arm and the finger drop, 100 the latter dropping down to engage the threads of the feed-screw 23. The carriage 16 is free to rock on the shaft 17, in view of which the upward swing of the arm 19 rocks the carriage in a direction to swing the arm 105 110

18 upward to disengage the nut 20 from the feed-screw 21 and also to lift the stylus of the sound box off the record cylinder 12. The finger 27 being now in engagement with 5 the threads of the feed-screw 23, and the nut 20 being disconnected from the feed-screw 21, the carriage 16 and the parts carried thereby, will be returned to starting position. The threads of the two feed-screws 10 run in the same direction, but rotation is in opposite directions. At the end of the return movement of the carriage, the finger 27 comes opposite a reduced unthreaded portion 31 of the feed-screw 23 and drops 15 down to inoperative position, as shown in Fig. 4, and at the same time the nut 20 drops down into engagement with the feed-screw 21, and the forward movement of the carriage again starts. In this manner the message 20 on the record cylinder is repeated until the machine is stopped. In the path of the free end of the arm 19, at the reduced portion 31 of the feed-screw 23, is a spring finger 32 which is struck by said arm at the 25 end of its forward travel, and thus absorbs the lateral shock.

The talking machine is driven by an electric motor 33 having a reducing belt or other driving connection 34 with the feed-screw 30 21. The motor is mounted on the bottom of the shelf 11 in the box 8, a suitable insulation 35 being provided. The shaft 36 of the motor 33 also actuates a switch which 35 controls the telephone circuit and the circuit of the motor. This switch comprises a series of contact points 37 located opposite contact strips 38 and normally spaced therefrom, so that said circuits are normally open. On the motor shaft is fast a pinion 40 39 which is in mesh with a gear wheel 40 loosely mounted on the reduced end 41 of a rod 42 carrying at its opposite end a bar 43 of insulation, which latter, in turn, carries the contact points 37. On the bottom of the 45 shelf 11 is mounted and suitably insulated therefrom, as indicated at 44, a bracket 45 carrying a tube 46 through which the rod 42 loosely passes. In the end of the tube which is adjacent to the gear wheel 40 are diametrically opposite recesses 47, and on the 50 back of the hub of said gear wheel are lugs 48 adapted to enter said recesses. When the lugs come in line with the recesses, the rod 42 is advanced by a spring 49 housed in the 55 tube 46 and bearing against an abutment 50 on the rod. This movement of the rod brings the contact points 37 against the contact strips 38 to close the circuits controlled by the same.

60 The gear wheel 40 is normally in mesh with the pinion 39, in which position of the former, the rod 42 is held retracted and the contacts 37 and 38 are separated. The rod is held in this position by turning the gear 65 wheel until its lugs 48 abut against the end

of the tube 46. If now the motor 33 starts, the gear wheel is rotated, and when the lugs come in line with the recesses 47, they enter the same, the rod being advanced by the spring 49 as hereinbefore described.

70 The contact strips 38 are mounted on the bottom of the shelf 11 and insulated therefrom by the insulation 44, and they are provided with binding posts. The contact points 37 also have binding posts. One of the contact points 37 is wired to a binding post 51, and the opposite contact strip 38 is wired to a binding post 52. These binding posts are mounted on one of the walls of the box 8, said wall also carrying other binding 80 posts 53 to which the remaining contact posts and strips are wired. The wires of the telephone circuit are connected to the binding posts 53.

To the binding posts 51 and 52 is connected the wiring of the protective circuit. This wiring comprises a conductor 54 connected to the binding post 51 and a conductor 55 connected to the binding post 52. At the doors, windows and other entrances to 90 the house these conductors have cross connections 56 in parallel, the same being so connected to the doors, windows and other parts that the protective circuit is open when the doors, etc., are properly closed, the opening of the doors or other parts resulting in the circuit being closed. It will therefore be seen that the protective circuit is normally open.

95 From the binding post 51 a conductor 57 leads to one side of the motor 33, and from the binding post 52 a conductor 58 leads to the other side of the motor. The motor circuit includes a suitable source 59 of electric energy. The wiring between the binding post 51 and its corresponding contact point 37 is indicated at 60, and the wiring between the binding post 52 and the contact strip 38 opposite said contact point is indicated at 61. In the conductor 57 is interposed a switch 62.

100 The system operates as follows: The protective circuit is normally open, and as the circuit of the motor 33 is connected thereto, the motor is also normally inoperative, and the circuits controlled by the motor-actuated switch are open. If now the protective circuit is closed by an intruder opening a window, or in any other way attempting to enter the house through an entrance which 115 is wired by the protective circuit, the motor circuit is also closed and the motor starts, whereupon the telephone circuit is closed and the talking machine is started as hereinbefore described. The circuit may be 120 traced as follows: from one side of motor by conductor 57 to binding post 51, conductor 54, cross connection 56 at the window or other place where the entrance is attempted, conductor 55, binding post 52, and conduc- 130

tor 58 to the other side of the motor. If the intruder should close the window or otherwise again open the protective circuit, the motor circuit will not be opened and 5 the motor will continue to operate the talking machine for the reason that when the motor started and the telephone circuit was closed, the contact post 37 of the wire 60 and the contact strip 38 of the wire 61 were also 10 brought together. Hence, if the protective circuit were opened, the motor circuit would remain closed, the circuit being now from one side of the motor by conductor 57 to binding post 51, conductor 60 to contact 15 point 37, contact strip 38, conductor 61, binding post 52, and by conductor 58 back to the other side of the motor. The alarm will therefore be given if the intruder should abandon the first attempt and seek another 20 entrance. As the system operates on a normally open circuit, no current is consumed while the system is idle.

I claim:

1. The combination of an alarm mechanism including an electric signal circuit, an electric motor for actuating said mechanism, a switch controlling the signal circuit, and means operated by the motor for closing said switch, said means comprising a reciprocatory rod connected to the switch, a gear wheel loose on the rod, said gear wheel having a stud, a stationary member having a recess located opposite the stud, and a pinion 25 on the motor shaft in mesh with the gear wheel when the stud of the latter is outside the recess, said gear wheel dropping out of mesh when the stud registers with and en- 30 35

ters the recess, whereby the aforesaid rod is released to close the switch.

2. An electric burglar alarm system comprising an alarm mechanism including an electric signal circuit, an electric motor for actuating said alarm mechanism, a switch controlling the signal circuit, a normally open protective circuit, an energizing circuit 40 for the motor, said circuit being connected to the protective circuit, a switch having connections with the energizing circuit for holding said circuit closed after the protective circuit is closed and thereafter 45 opened, and means operated by the motor for controlling the aforesaid switches.

3. An electric burglar alarm system comprising a telephone circuit, a talking machine the sound waves of which are conducted into the transmitter of the telephone, a switch controlling the telephone circuit, an electric motor operatively connected to the talking machine, a normally open protective circuit, an energizing circuit for the 50 motor, said circuit being connected to the protective circuit, a switch having connections with the energizing circuit for holding said circuit closed after the protective circuit is closed and thereafter opened, and 55 means operated by the motor for controlling the aforesaid switches.

In testimony whereof I affix my signature in presence of two witnesses.

SALVATORE D. TOMASO.
